(57) **CLAIM**

The ornamental design for a spotting scope, as shown and described.

DESCRIPTION

FIG. 1 is a front elevation view of a spotting scope, showing my new design;

FIG. 2 is a left side perspective view thereof;

FIG. 3 is a bottom plan view thereof;

FIG. 4 is a left side elevation view thereof; the right side elevation view is identical;

FIG. 5 is a top plan view thereof; and,

FIG. 6 is a rear elevation view thereof.

The broken line in the drawings depicts unclaimed portions of the scope only and forms no part of the claimed design.

1 Claim, 6 Drawing Sheets
